(57) **CLAIM**

The ornamental design for a tamper-resistant quad receptacle with two controlled outlets and two live outlets, as shown and described.

DESCRIPTION

FIG. 1 is a perspective front view of a tamper-resistant quad receptacle with two controlled outlets and two live outlets incorporating the new design;

FIG. 2 is a front view thereof;

FIG. 3 is a back view thereof;

FIG. 4 is a right side view thereof;

FIG. 5 is a left side view thereof;

FIG. 6 is a bottom view thereof; and,

FIG. 7 is a top view thereof.

The broken lines shown in the drawings are for purposes of illustrating portions of the tamper-resistant quad receptacle with two controlled outlets and two live outlets that form no part of the claimed design.

1 Claim, 7 Drawing Sheets
